Charles W. Cram,
INVENTOR
BY *Victor J. Evans*

ATTORNEY

UNITED STATES PATENT OFFICE.

CHARLES W. CRAM, OF BIRMINGHAM, ALABAMA, ASSIGNOR OF ONE-THIRD TO EDWARD E. COLMER, OF MCHENRY, MISSISSIPPI.

CYLINDER HEAD.

Application filed November 29, 1927. Serial No. 236,497.

My present invention has reference to internal combustion engines and my object is to provide the cylinder head of this type of engines with a supplemental or auxiliary 5 compression chamber that communicates with the compression chamber in the head, and wherein the passage between the auxiliary and main or ordinary compression chamber is controlled by a valve operable to 10 establish communications between these chambers or to close such communication and whereby when the auxiliary chamber is closed by the valve the pistons will operate to turn the engine at normal or ordinary speeds with 15 a comparatively small consumption of fuel, but when the valve is open a greater compression space is provided and while more fuel is required the pistons will operate the engine to cause the same to travel at a greater speed 20 and with more power, the valve being opened when the automobile operated by the engine is traveling inclines at high speed and upon other occasions when high speed is desired.

To the attainment of the foregoing the invention consists in the improvement as hereinafter described and definitely claimed.

In the drawings:

Figure 1 is a sectional view through the upper portion of an engine block, embodying 30 my improvement.

Figure 2 is a side elevation thereof to better illustrate the manner in which the valve is held seated or is spring influenced to unseated position.

In the drawings I have deemed it necessary to show only one of the piston cylinders of an engine block 1, and one of the compression chambers 2 on the head 3 for the block. The head is provided with the usual spark 35 plug opening 4 and to one side of said opening the head is integrally formed with what I will term an auxiliary compression chamber 5. A port 6 establishes a communication between the auxiliary compression chamber 5 and the main compression chamber 2 in the head 3. By reference to Figure 1 of the drawings it will be noted that the compression chamber is cast with a head in a manner to permit of a circulation of water 40 entirely around the auxiliary compression chamber and likewise that the compression chamber is extended a considerable distance above the top of the head proper and is internally threaded. The open outer end of 45 the compression chamber has screwed there-

in a flanged member or cap nut 7 which is centrally and integrally formed with a depending sleeve portion 8. The lower wall of the compression chamber is flared toward the port or opening 6 and the portion of the 60 lower wall around the said opening is beveled to provide a seat for a valve 9. The stem 10 for the valve extends through an opening in the sleeve 8 and through the cap nut 7. The sleeve has fixed thereon, adjacent to its 65 outer end a washer 11 which is contacted by a helical spring 12 that surrounds the stem 10. The spring also contacts with a washer 13 arranged on the top of the flanged cap nut 7. The outer end of the rod 10 is rounded 70 and is received in a longitudinal groove provided in a slide block 14. The inner wall 15 of the groove is beveled. The block 14 is fixedly secured upon an operating rod 16, and one end of this rod is disposed in a position 75 convenient to the driver of the automobile that is operated by the engine.

The spring 12 will normally unseat the valve 9 but the wedge block 14, when the rod 16 is moved to one position, will hold the valve 80 seated. When the valve is seated, the piston in the engine cylinder will compress the fuel in the compression chamber 2 of the head 3, and the engine may be speeded up to say 45 miles per hour. When the valve is closed a 85 smaller amount of fuel is used. When the rod is moved to permit of the opening of the valve 6, the fuel is compressed in both the compression chambers 2 and 5 which, of course, will require a larger volume of fuel, 90 but the explosion thereof will impart a greater power and speed to the piston so that the engine will revolve at a high speed which is desirable for hill climbing and for other purposes.

While I have illustrated a satisfactory embodiment of my improved device my features of invention are capable of extended application and I do not wish to be restricted to the specific structure herein shown and described. 95 100

Having described the invention, I claim:

1. An internal combustion engine having a head provided with an auxiliary compression chamber and having a port which establishes a communication between the auxiliary compression chamber and the chamber in the head, a cap nut closing the outer and open end of the auxiliary compression chamber, a valve for closing the port between the compression chambers, a stem for the valve passing 105 110

through the cap nut, spring means influencing the spring to unseat the valve, a block having a wedge groove therein which is movable over the outer end of the valve stem, and an operating rod for said block.

2. A head for the cylinder block of an internal combustion engine, having a compression chamber, and having an outwardly extending auxiliary compression chamber, and provided with a port which establishes a communication between both compression chambers, a cap nut screwed in and closing the auxiliary compression chamber and having a sleeve extension, a valve for closing the port

between the compression chambers, a stem 15 for the valve directed through the sleeve and through the cap nut, a stop element on the stem outward of the cap nut, a coil spring surrounding the stem and exerting a pressure against the stop element and the cap nut, said stem having an outer rounded end, a block having a longitudinal groove whose inner wall is beveled, and in which groove the said outer end of the stem is received, and a slideable rack fixedly secured to the block, for the purpose set forth.

In testimony whereof I affix my signature.
CHARLES W. CRAM.
